[57] ABSTRACT

A roller drive agitating and spinning mechanism has an improved device for retracting a roller from the drive train when the roller is not transmitting power. The retractor device has a pad of ultra-high molecular weight polyethylene which is spring-biased against the roller surface of polyurethane at an angle to cause the roller to retract. The pad also serves to wipe wear debris and other foreign matter from the roller surface during operation of the mechanism to maintain the roller surface smooth and clean.

ROLL RETRACTOR FOR ROLLER DRIVE MECHANISM

This invention relates to a domestic appliance and, more particularly, to an improved roller drive mechanism for agitating and spinning in a clothes washer.

Roller drive mechanisms, such as taught in U.S. Pat. to Brucken No. 3,087,321, issued Apr. 30, 1963, use certain self-energizing rollers as idler members between the motor and the driven member for producing either agitate or spin. Such roller drive mechanism may include a reversible motor, the reversibility of which determines whether agitate or spin is produced. Each of the rollers is provided with a resilient tire portion of polyurethane or the like as the motion transmitting surface. During agitation, one of the rollers is in power transmitting relationship while the other roller is overridden and merely idles. During the life of the roller, the surface of the tire portion may become tacky and wear unevenly due to the scuffing action on the tire surface of the roller not transmitting power. Such scuffing is aggravated where the tire surface decomposes slightly due to hydrolysis or due to some unreacted resin working its way out of the tire onto the surface thereof. This scuffing action tends to form flat spots on the roller tire. Moreover, such scuffing produces wear debris which accelerates tire wear. When this wear phenomenon occurs, a smooth driving connection is lacking between the drive motor and the driven member with the result that the mechanism becomes noisy.

Accordingly, it is an object of this invention to provide an improved roller retraction device for a roller drive mechanism of the type disclosed in U.S. Pat. to Brackman et al. No. 3,287,942 issued Nov. 29, 1966.

Another object of this invention is the provision in a roller drive spinning mechanism of a roller retraction device which wipes the roller surface clean as the mechanism operates.

A more specific object of this invention is the provision in a roller drive agitating and spinning mechanism of a device for retracting a polyurethane-tired roller, said device including a pad of ultra-high molecular weight polyethylene spring-biased against the tire to assist in making the roller self-energizing and to wipe wear debris and other foreign matter from the roller tire surface, thereby to maintain the tire surface smooth and clean.

Further objects and advantages of the present invention will be apparent from the following description, reference being had to the accompanying drawings wherein a preferred embodiment of the present invention is clearly shown.

In the drawings:

FIG. 1 is a side sectional view, partly in elevation, taken along line 1—1 in FIG. 2 to show the improved roller drive agitating and spinning mechanism of this invention;

FIG. 2 is a top elevational view of the agitating and spinning mechanism of FIG. 1;

FIG. 3 is a sectional view of a self-energizing roller taken along line 3—3 in FIG. 4 and illustrating the roller retraction device of this invention;

FIG. 4 is a top elevational view of the roller retractor assembly;

FIG. 5 is a fragmentary sectional view taken along line 5—5 in FIG. 3;

FIG. 6 is a fragmentary elevational view taken along line 6—6 in FIG. 3; and

FIG. 7 is a schematic sectional view, partly in elevation, of a clothes washer provided with the improved roller drive agitating and spinning mechanism of this invention.

Refer now to FIG. 7 wherein a top-opening clothes washer 20 is illustrated. The clothes washer includes a nested tub assembly 24. The assembly includes an open-top, imperforate wall water container 26 and a perforate wall spin basket 28. Perforations are coextensive with the cylindrical sidewall of the spin basket. An annular plastic subtop 30 is sealingly clamped to the open top of the water container 26. The subtop circumscribes the open top of the water container and extends over a rim 33 forming the top opening of the spin basket 28 to define an access collar 36 between the top opening in the clothes washer cabinet and the top opening 33 of the spin basket.

The water container 26 and, thus, the tub assembly 24 is mounted on a suspension system more fully taught in U.S. Pat. to Brucken, No. 3,493,118, issued Feb. 3, 1970. The tub assembly includes an agitator 44 which with the spin basket 28 is connected in movement effecting relationship to a drive mechanism or movement effecting means shown generally at 50. The drive mechanism may be of a roller-drive type taught more fully in the aforementioned U.S. Pat. No. 3,087,321. In general, mechanism 50 may be operated through a reversible motor 52 in one manner to vertically reciprocate or oscillate the agitator 44 for washing clothes in the tub assembly. When mechanism 50 is operated in another manner, the spin basket 28 is rotated with respect to the water container 26 for centrifuging washing fluid from the clothes in the spin basket.

A peripheral fill system is carried and supported on the annular plastic subtop 30. The under side of the subtop includes a pair of integral ribs 54, 56 which define a channel to receive a flexible fill tube 60 arranged around the top opening 33 of the spin basket and adapted to direct a series of fan-shaped sprays downwardly into the spin basket. For additional details regarding the peripheral fill system for clothes washer 20, reference may be had to U.S. Pat. to Fish et al., No. 3,663,975, issued May 23, 1972.

Roller drive mechanisms for selectively spinning a tub and reciprocating or oscillating an agitator are taught in the aforementioned Brucken patent; in Sisson U.S. Pat. No. 3,060,712 issued Oct. 30, 1962, 3,165,911 issued Jan. 19, 1965, and 3,174,596 issued Mar. 23, 1965; and in Fosler and Fosler et al. U.S. Pat. No. 3,223,211 and 3,314,257 issued Dec. 14, 1965, and Apr. 18, 1967, respectively.

This invention is directed to an improved roller retractor device of the type taught in the aforementioned Brackman et al. patent. Such retractor devices are for use in combination with a train of motion transmitting rollers in roller drive mechanisms and provide for removal of the roller not driving, in response to the direction of motor rotation, thereby eliminating tire wear due to scuffing of the tread thereof.

Turning now to FIGS. 1, 2 and 7, the agitating and spinning mechanism 50 will now be described more particularly. The mechanism includes a $\frac{1}{3}$ horsepower, split phase, single speed, 1,725 r.p.m., four pole, re-

versible motor 52. The motor 52 has a motor shaft 70 drivably connected by belt 72 to pulley 74 on reversible power or drive shaft 76. Power shaft 76 has a spin portion or spin driver 78 and a reduced diameter agitate portion or agitate driver 80. At the bottom of the power shaft is a drain pump 82 adapted through impeller 83 in one direction of rotation to pump water from tub 26 to drain through conduits 84 and 86. Suitable bearings 88, 90 journal the power shaft in a mechanism support 92.

On the same general plane as the spin driver 78 is a spin driven roller means or spin wheel 94 of the type taught in the aforementioned Fosler et al. U.S. Pat. No. 3,314,257, while an agitate wheel or agitate driven roller means 96 lies in the same plane as the agitate driver 80. Interposed between the agitate driver 80 and the agitate wheel 96 is the agitate roller or idler 98, spring-loaded and laterally floating to make it self-energizing according to the concept of the aforementioned Brucken U.S. Pat. No. 3,087,321. Similarly, a self-energizing spin roller or idler 100 lies between the spin driver 78 and the spin wheel 94.

In general, operation of pulley 74 and power shaft 76 in the direction of the solid arrows (FIG. 2) will drive the agitate wheel 96 through the agitate roller 98 — this driving motion being translated into reciprocation of agitate shaft 104. Conversely, with power shaft 76 reversed as shown by the dashed arrows, the roller 100 will be drawn into a wedging driving connection between the spin drive member 78 and the spin wheel 94 to rotate the spin shaft 106.

In roller drive mechanisms one idler roller, due to overrunning, may scuff against the surface of its respective wheel while the other roller is in the power train transmitting the driving force. This scuffing action may create wear problems and produce wear debris on the surface of the tire of the non-driving roller. Other foreign matter in the environment of the washer and/or working out of the roller tire itself may find its way onto the roller surface. In this invention an improved roller retractor device shown generally at 110 solves these problems by withdrawing the non-driving roller from scuffing engagement with its respective driven wheel whenever the roller is being overrun and, at the same time, wiping the roller surface clean.

At this point, it should be noted that the retractor device 110 is shown only on the spin roller 100 although it could as well be used with the agitate roller 98.

The roller retractor assembly 110 will now be described with reference to FIGS. 3-6. The assembly is comprised of a spin roller 100 which has a polyurethane tire 112 molded onto an aluminum die cast insert 114. A sintered bronze bushing 116 is pressed into the insert to form a hub for the roller.

For supporting the roller 100 the retractor assembly includes a U-shaped support bracket 120 having an upper support arm 122 and lower support arm 124 held apart at their terminal or distal ends by a spool-like spacer sleeve 126. Sandwiched between the arms 122, 124 are a pair of pivot arms or links 130, 132, an upper pivot arm 130 having a socket portion 134 for rotatably journaling the upper end 136 of the bushing 116 while the socket portion 138 of the lower pivot arm 132 journals the lower end 140 of the bushing. A bowed bronze washer 141 provides the correct balance of tension in the clearance gap so the pivot arms may slidably shift relative to the bracket without rattling. The diameter of

the bushing 116 is oversized relative to the spacer sleeve 126 to provide a sloppy fit. In view thereof the socket portions of the pivot arms as well as the roller 100 journaled therein are permitted to shift in all lateral directions around the spacer sleeve.

Elongated slots 144, 146 are formed in the upper and lower bracket arms 122, 124, respectively, to form a pivot point for the pivot arms. The upper and lower pivot arms have socketed end portions 148, 150, respectively, slidably movable within the respective slots. Helically coiled spin roller tension springs 152, 154 extend between the socketed ends of the pivot arms and bracket 120 to bias the spin roller and its bushing 116 toward the spacer sleeve 126, i.e., to make the roller self-energizing. A leaf spring 160 is attached to the outside of the support bracket by rivets 162 and also helps to make the roller self-energizing. Lanced-out tangs 164 cooperate with holes 166 in aligning the leaf spring with the bracket.

On the distal end of leaf spring 160 is a pad 170 adapted to bear against the outer surface of the roller tire 112. The pad is ultra-high molecular weight polyethylene marketed by Dixon Corporation under the trademark PENLON. Generally, pad 170 engages the roller tire surface along a straight line. However, a slight contour may develop during the run-in of the agitate and spin mechanism, after which the pad has substantially no wear rate. Leaf spring 160 is adapted to provide approximately 16 to 18 ounces of force against the roller surface. This force is not critical. The guidelines are merely that if the force is too light, the pad will have no effect; whereas if the force is too heavy, there will be excessive pad wear.

With reference to FIG. 1, the retractor assembly 110 is attached to support 92 of the mechanism by a bolt 174 which extends through the spacer sleeve 126 of the roller 100 and threadedly engages the support. A tang 176 struck upwardly from the support bracket arm 120 extends into a hole or notch 178 in the support to position the retractor assembly relative to the spin driver 78 and spin wheel 94.

Bosses, such as 180 and 182, on pivot arm 130, 132, respectively, extend through the respective slots 144 and 146 in the support bracket to provide the pivot point about which the pivot arms move when the spin roller 100 retracts.

The operation of the roller retractor device 110 is best understood with reference to FIGS. 1 and 2. The purpose of the improved device is to eliminate the wear on the tire surface of the spin roller 100 by retracting the roller. This eliminates the scuffing action of the roller 100 against the wheel 94 which would occur in an overrunning relationship therebetween. The improved device also wipes the tire surface as the roller rotates so that foreign matter will not accumulate and accelerate tire wear.

AGITATE OPERATION

For agitate operation, the motor 52, pulley 74 and power shaft 76 rotate counterclockwise (FIG. 2). The agitate driver 80, being keyed to the power shaft, drives the agitate roller 98. The agitate roller is pushed into light contact with both the agitate driver 80 and agitate wheel 96 by the agitate roller tension springs 152, 154.

As the shaft starts to rotate, the floating action of the roller on its spacer permits the roller to be pulled by ro-

tational force into positive contact with the surfaces of the agitate driver 80 and the agitate wheel 96. Thus, the rotational torque of the motor is transmitted through the agitate roller to cause the agitate wheel to rotate clockwise. During agitation operation the spin roller 100 also rotates, being driven by the spin driver 78. However, due to the direction of motor rotation, the angle of force of pad 170 on the spin roller, and the floating action of the roller on its spacer, the rotational force imparted by the spin driver pushes the spin roller out of contact with the spin wheel 94. The spin wheel remains stationary during the agitate period.

SPIN OPERATION

For spin operation, the motor 52, pulley 74 and power shaft 76 rotate clockwise (FIG. 2). The spin driver 78, being keyed to the power shaft, drives the spin roller 100.

The spin roller is pushed into light contact with both the spin driver and the spin wheel 94 by the spin roller tension springs 152, 154 and leaf spring 160. As the motor starts to rotate, the floating action of the spin roller on its spacer 126 permits the roller to be pulled by rotational force into positive contact with the surfaces of the spin driver 78 and the spin wheel 94. Thus, rotational torque of the motor is transmitted through the power shaft and spin roller to cause the spin wheel to rotate clockwise to spin the tub 28. During spinning operation, the agitate roller 98 is being driven by the agitate driver 80. However, due to the direction of rotation of the motor and power shaft and the floating action of the roller on its spacer, the roller tends to be pushed away from the agitate wheel 96. Thus, the agitate roller is in extremely light contact with the agitate wheel and the agitate wheel does not rotate.

While the embodiment of the present invention as herein disclosed constitutes a preferred form, it is to be understood that other forms might be adopted.

What is claimed is:

1. In an agitating and spinning mechanism comprising two shaft means concentrically arranged, support means for said shaft means, spin driven roller means drivably connected to one of said shaft means for rotating said one of said shaft means, means drivably connected to the other of said shaft means for motivating said other of said shaft means including agitate driven roller means rotatably carried by said support means, reversible power shaft means, first self-energizing roller means laterally movable with respect to said spin driven roller means and said power shaft means for selectively wedgingly engaging said spin driven roller means and said power shaft means to motion transmittingly connect said power shaft means with said spin driven roller means when said power shaft means is operating in one direction for inducing spinning, and second self-energizing roller means laterally movable with respect to said agitate driven roller means and said power shaft means for selectively wedgingly engaging said agitate driven roller means and said shaft means to motion transmittingly connect said power shaft means with said agitate driven roller means when said power shaft means is operating in the reverse direction for inducing agitating, one of said first or second self-energizing roller means including an idler roller and means for moving said idler roller out of wedging engagement with its respective driven roller means in response to the direction of operation of said power shaft

means, the improvement wherein said means for moving said idler roller out of said wedging engagement includes a retractor pad biasingly, slidably engageable with the outer driving surface of said idler roller opposite from said power shaft and generally between said respective driven roller means and said power shaft, said pad in response to the biasingly, slidably engagement thereof with the outer driving surface of said idler roller for moving said idler roller also engaging said outer surface in a manner sufficiently coextensive therewith to wipe said outer surface free of wear debris, thereby to maintain said outer surface smooth and clean.

2. In a spinning mechanism comprising spin shaft means, support means for said spin shaft means, spin driven roller means drivably connected to said spin shaft means for rotating said shaft means, power shaft means operable in a first and second manner, self-energizing roller means movable with respect to said spin driven roller means and said power shaft means for selectively wedgingly engaging said spin driven roller means and said power shaft means to motion transmittingly connect said power shaft means with said spin driven roller means when said power shaft means is operating in a first manner for inducing spinning, said self-energizing roller means including a rotatable idler roller and means for moving said idler roller out of wedging engagement with the spin driven roller means in response to the operation of said power shaft means in said second manner, the improvement wherein said means for moving said idler roller out of said wedging engagement includes a retractor pad biasingly, slidably engageable with the outer driving surface of said idler roller opposite from said power shaft means and generally between said spin driven roller means and said power shaft means, said pad in response to the biasingly, slidably engagement thereof with the outer driving surface of said idler roller for moving said idler roller also engaging said outer surface in a manner sufficiently coextensive therewith to wipe said outer surface free of wear debris as said idler roller rotates, thereby to maintain said outer surface smooth and clean.

3. The spinning mechanism of claim 2 wherein said self-energizing roller means includes a U-shaped bracket holding said idler roller between the distal ends thereof and wherein said pad is carried on a leaf spring extending from the base of said bracket toward said idler roller.

4. The spinning mechanism of claim 3 wherein the outer surface of said idler roller is part of a polyurethane tire and said retractor pad is ultra-high molecular weight polyethylene having a dimension as wide as the outer surface of said idler roller.

5. A roller retractor assembly for a roller drive mechanism comprising bracket means adapted to be affixed adjacent a train of motion transmitting roller means, said bracket means having spacer means and means forming a pivot point, pivot arm means having a journal portion and a socketed pivot portion, an idler roller journaled in said journal portion and having hub means larger in diameter than said spacer means and around said spacer means, a retractor pad parallel to the axis of said idler roller and movable toward and away from said idler roller, and means for biasing said retractor pad into engagement with the outer driving surface of said idler roller and for biasing said pivot arm means away from said bracket means and adapted thereby for

movement toward said train of motion transmitting roller means, whereby the direction of rotation of said idler roller will determine the direction said pivot arm means will pivot about the pivot point in said bracket means thereby to add the idler roller to said train of motion transmitting roller means or to retract said idler roller therefrom, said pad in response to the biasing thereof into engagement with the outer driving surface of said idler roller also engaging said idler roller along a line on the outer surface thereof sufficient to wipe said outer surface free of wear debris, thereby to main-

tain said outer surface smooth and clean.

6. The retractor assembly of claim 5 wherein said idler roller has a polyurethane tire and said retractor pad is ultra-high molecular weight polyethylene.

7. The retractor assembly of claim 5 wherein said means for biasing includes a leaf spring between said pad and said bracket means and a coil spring between the socketed pivot portion of said pivot arm and said bracket means.
